CARRYING CASE FOR SEWING MACHINES
Hans Gugelot and Herbert Lindinger, Ulm (Danube),
Germany, assignors to Gritzner-Kayser A.G., Karls-
ruhe-Durlach, Germany

Filed Feb. 14, 1962, Ser. No. 173,277

Claims priority, application Germany Feb. 20, 1961
5 Claims. (Cl. 45—68.2)

The invention relates to carrying cases for sewing machines and is particularly concerned with the construction of a hood in the form of a trunk having built in containers for receiving the sewing accessories.

The upper parts of machines while they are not in use are frequently covered by a trunk-like hood placed in inverted position over the machine.

As a rule the hood does not conform to the shape of the upper part of the sewing machine but is in practice in the form of a rectangular body. As a result a free space exists between the walls of the hood and actual upper part of the sewing machine which can be utilized for accommodating small objects such as, for example, the accessories for the sewing machine.

Attempts have already been made to build special receptacles into the hood to receive the sewing accessories. These known propositions, however, do not provide optimum solutions of the problem because actually they result in the hood being enlarged so that even more space is required. Moreover, the receptacles built into the known hoods are not readily accessible.

It is therefore an object of the invention to provide a hood-like cover for sewing machines, the outlines of which do not exceed the sides of the conventional trunk-like hoods, where the waste space is utilized in the best manner possible so that additional receptacles are obviated.

In accordance with a further object of the invention, the receptacles for the sewing accessories are arranged in a manner to save space while at the same time greater accessibility to the receptacles or containers is provided without the necessity of complicated manipulations.

Accordingly, the invention provides that the receptacles or containers are arranged in the upper part of the trunk-like hood parallel to the upper edges of the longitudinal walls of a bridge which separates the receptacles, which are adapted to be closed by cover portions each of which constitutes a part of the wall of the hood.

In a preferred embodiment of the invention the bridge which separates the receptacles from one another is arranged along the center line of the trunk-like hood; it may be hollow and open along the side facing the sewing machine so that the yarn roll pins extending upwardly from the machine may be accommodated in a space preserving manner. Furthermore, a grip for the trunk can be secured to the bridge.

To prevent the sewing accessories from becoming mixed up while the machine is being transported, the receptacles are sub-divided by intermediate walls which are faced with corresponding intermediate walls in the cover portions which are constructed in such a manner that in the closed condition of the cover portions, closed hollow spaces are formed for accommodating the sewing accessories.

Further advantageous features and objects of the invention, as well as details about the advantages obtained, will become apparent from the following specification with reference to the embodiment of the invention illustrated in the accompanying drawings in which:

FIG. 1 is a perspective view of the trunk-like closed hood;

FIG. 2 shows the hood with the lid portions in open condition; and,

2

FIG. 3 is a section taken along the line III—III in FIG. 2 with the lid portions in partly opened position.

The trunk or case which is generally indicated at 1 comprises in a known manner the case bottom 2 and the hood 3. These parts are connected with one another by means of lock joints 4 at their side walls 5, 6 in a manner that the hood 3 can be completely removed in order to render the sewing machine 7 which is fastened to the bottom 2 of the casing in operative condition.

10 Two receptacles 9 are defined in a casing installed in the upper part of the hood 3 parallel to the upper edges of the longitudinal walls 8, the bottoms 10 of which close the inner space of the hood 3 at the top. A bridge 11 separates the receptacles 9 from one another. In the 15 embodiment illustrated the bridge 11 extends longitudinally of the center of the hood 3. It is hollow and open at the bottom to provide space for the yarn roll pins 13 of the sewing machine 7. A grip 12 is secured to the bridge 11 by means of which the entire case or 20 trunk is carried.

The receptacles 9 may be closed by means of the cover portions 14 which present longitudinal walls 15 and 16 and transverse walls 17 (FIG. 2). In the closed condition of the receptacles 9 the longitudinal walls 15 and 16 25 constitute a part of the longitudinal walls 8 of the hood 3 while the transverse walls 17 come to rest along those parts of the end walls 5 of the hood 3 which close the receptacles 9 during the opened condition of the cover portions 14.

30 The transverse walls 17 are provided with studs 18 to provide pivotal support for the cover portions 14. The studs 18 engage the bores 19 that are provided in the side walls 5. Latches 20 are provided on the bridge 11 and locks 21 snap into engagement with the latches on 35 the cover portions 14 for locking the cover portions.

The longitudinal walls 15 of the cover portions 14 are obliquely cut along their lower edges 22 substantially tangentially with respect to the pivot axes of the studs 18 in order to avoid the forming of slots between the 40 cover portions 14 and the longitudinal walls 8 when the receptacles 9 are closed. Furthermore, the adjacent edges 23 of the longitudinal walls 8 of the hood 3 are adapted to match the oblique cuts on the longitudinal walls 8.

45 The receptacles 9 are sub-divided into individual compartments by intermediate walls 24 to permit orderly arrangement of the different sewing accessories. As the receptacles 9 are closed the intermediate walls 25 arranged on the cover portions 14 become seated on the intermediate walls 24. In this manner the sewing accessories cannot become mixed up during the transportation of the sewing machine in the casing.

Having now described our invention with reference to the embodiment illustrated in the drawings, we do not 55 wish to be limited thereto, but what we desire to protect by Letters Patent of the United States of America is set forth in the appended claims.

We claim:

1. Carrying case for sewing machine of the type comprising a base and a hood disposed in inverted position on said base, said hood having receptacles for accessories or the like arranged in the upper portion thereof and having parallel longitudinal side walls presenting upper edges and end walls having portions projecting above said side walls, said receptacles being defined in a casing mounted in the upper portion of said hood, said casing including a bridge member extending generally centrally and longitudinally of said hood and a pair of bottom members separated by said bridge member, said bottom members and bridge member closing the upper end of said hood, and a pair of closure members for said casing having each a first longitudinal member defining in

closed condition a continuation of one said longitudinal side wall between said portions of said end walls extending above said side wall and having each a second longitudinal member defining in closed condition a top closure member extending between said first longitudinal member and said bridge, and pivot support members including studs extending between the ends of said closure members and adjacent projecting portions of said end walls.

2. Carrying case for sewing machine of the type comprising a base and a hood disposed in inverted position on said base, said hood having receptacles for accessories or the like arranged in the upper portion thereof and having parallel longitudinal side walls presenting upper edges and end walls having portions projecting above said side walls, said receptacles being defined in a casing mounted in the upper portion of said hood, said casing including a bridge member extending generally centrally and longitudinally of said hood and a pair of bottom members separated by said bridge member, said bottom members and bridge member closing the upper end of said hood, and a pair of closure members for said casing having each a first longitudinal member defining in closed condition a continuation of one said longitudinal side wall between said portions of said end walls extending above said side wall and having each a second longitudinal member defining in closed condition a top closure member extending between said first longitudinal member and said bridge, and pivot support members including studs extending between the ends of said closure members and adjacent projecting portions of said end walls, said bridge being hollow and open at the bottom to receive projecting components of a sewing machine.

3. Carrying case for sewing machine of the type comprising a base and a hood disposed in inverted position on said base, said hood having receptacles for accessories or the like arranged in the upper portion thereof and having parallel longitudinal side walls presenting upper edges and end walls having portions projecting above said side walls, said receptacles being defined in a casing mounted in the upper portion of said hood, said casing including a bridge member extending generally centrally and longitudinally of said hood and a pair of bottom members separated by said bridge member, said bottom members and bridge member closing the upper end of said hood, and a pair of closure members for said casing having each a first longitudinal member defining in closed condition a continuation of one said longitudinal side wall between said portions of said end walls extending above said side wall and having each a second longitudinal member defining in closed condition a top closure member extending between said first longitudinal member and said bridge, and pivot support members including studs extending between the ends of said closure members and adjacent projecting portions of said end walls, said bridge being hollow and open at the bottom to receive projecting components of a sewing machine, and a carrying handle being secured to said bridge intermediate said second longitudinal members.

4. Carrying case for sewing machine of the type comprising a base and a hood disposed in inverted position

on said base, said hood having receptacles for accessories or the like arranged in the upper portion thereof and having parallel longitudinal side walls presenting upper edges and end walls having portions projecting above said side walls, said receptacles being defined in a casing mounted in the upper portion of said hood, said casing including a bridge member extending generally centrally and longitudinally of said hood and a pair of bottom members separated by said bridge member, said bottom members and bridge member closing the upper end of said hood, and a pair of closure members for said casing having each a first longitudinal member defining in closed condition a continuation of one said longitudinal side wall between said portions of said end walls extending above said side wall and having each a second longitudinal member defining in closed condition a top closure member extending between said first longitudinal member and said bridge, and pivot support members including studs extending between the ends of said closure members and adjacent projecting portions of said end walls, said bridge being hollow and open at the bottom to receive projecting components of a sewing machine, said receptacles having separating walls defining compartments and said cover portions having corresponding separating walls registering in closed condition with said separating walls in said receptacles and defining closed hollow spaces therewith.

5. Carrying case for sewing machine of the type comprising a base and a hood disposed in inverted position on said base, said hood having receptacles for accessories or the like arranged in the upper portion thereof and having parallel longitudinal side walls presenting upper edges and end walls having portions projecting above said side walls, said receptacles being defined in a casing mounted in the upper portion of said hood, said casing including a bridge member extending generally centrally and longitudinally of said hood and a pair of bottom members separated by said bridge member, said bottom members and bridge member closing the upper end of said hood, and a pair of closure members for said casing having each a first longitudinal member defining in closed condition a continuation of one said longitudinal side wall between said portions of said end walls extending above said side wall and having each a second longitudinal member defining in closed condition a top closure member extending between said first longitudinal member and said bridge, and pivot support members including studs extending between the ends of said closure members and adjacent projecting portions of said end walls, each said first longitudinal member having a free edge adjacent the corresponding upper edges of a side wall cut obliquely substantially tangentially with respect to pivot axis of the associated pivot studs.
